CLAIM

The ornamental design for a toilet paper storage basket, as shown and described.

DESCRIPTION

FIG. 1 is a front perspective view of a toilet paper storage basket, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an open state diagram.

The evenly broken lines in the drawings illustrate the portions of the toilet paper storage basket, which form no part of the claimed design. The unevenly broken lines representing stitching are part of the claimed design.
